UNITED STATES PATENT OFFICE.

CHARLES S. JOHNSON, OF CHAMPAIGN, ILLINOIS.

MEASURING HOPPER.

Application filed June 4, 1923. Serial No. 643,294.

To all whom it may concern:

Be it known that I, CHARLES S. JOHNSON, a citizen of the United States, and a resident of Champaign, county of Champaign, and 5 State of Illinois, have invented a certain new and useful Measuring Hopper; and I do hereby declare that the following is a full, clear, and exact description thereof, reference being had to the accompanying drawings, in which like numerals refer to like parts.

This invention relates to improvements in the valve mechanism for controlling the operation of measuring hoppers, used in measuring dry material of any kind and particularly in measuring and loading crushed stone and the like for making concrete.

There has always been trouble in operating the cut-off valve mechanism because of 20 the pressure of the load of sand, gravel or stone above it and failure of valve to close completely because large particles of material would become pinched in the valve, preventing full closing and causing leakage of 25 smaller particles. This valve is usually mounted at the outlet opening of a large bin adapted to receive a large quantity of sand or gravel or crushed stone. Therefore, when 30 the valve is being closed, it has to cut through the body of stone or sand at the outlet and in so doing should best be free to move material ahead of and out of the path of the valve. In this movement one trouble has been that the material would wedge be- 35 tween the valve and the adjacent structure and block the closing movement of the valve. Heretofore there was no means of forcing out of its path enough material to permit the complete closing of the valve. The up- 40 ward and forward crowding movement would have to act against the entire weight of the material above, which might be several feet deep and final forward movement was prevented by particles wedged in front 45 of the valve.

Therefore, an object of this invention is to overcome the foregoing difficulties in the construction heretofore used. One means for overcoming the disposition of the material to wedge between the knife and the adjacent parts is by curving the advancing edge of the valve so it will have a shearing movement to crowd the material forward of the valve instead of wedging it between 50 the valve and adjacent structure. Another feature of the invention in this connection is

the provision of an open chamber immediately above the valve that is not full of material and into which the material may be crowded up ahead and out of the way as the 60 valve closes and thus permit its closure.

Most constructions of this kind have a plurality of bin sections for materials of different kinds, such as sand and stone for concrete, and a corresponding plurality of 65 measuring hoppers, and each hopper has a valve for controlling the inlet thereto that must be operated by hand.

A feature of this invention is in the means for operating the valves for the two hoppers, whereby they may be simultaneously opened and closed. Thus in handling material for concrete, the sand and stone are fed through into the hoppers and loaded into the trucks below simultaneously, but in 70 different quantities, proportioned according to the mixture formula desired for the concrete that is to be made. It is important, therefore, that both hoppers be filled and discharged together.

The full nature of the invention will be understood from the accompanying drawings and the following description and claims:

In the drawings, Figure 1 is a side elevation of a pair of measuring hoppers, partially broken away, and their associated valve mechanisms for controlling the inlet and outlet of the hoppers. Fig. 2 is the same as the lower part of Fig. 1, with the valves 85 open instead of closed. Fig. 3 is a plan view of the upper valve construction. Fig. 4 is a section on the line 4-4 of Fig. 3 with the valve closed. Fig. 5 is the same as Fig. 4 with the valve only partially closed. Fig. 90 95 6 is a plan view of the right-hand valve structure in Fig. 3, showing the valve open.

The particular construction herein shown and described has been made, adapted and used in connection with structures for measuring and loading loose material, such as gravel, sand, stone and the like for concrete. But the invention is not limited to the sort of loose material handled nor to the purpose for which the material is intended. It may 100 be employed in any situation where loose material like sand, gravel or grain is to be measured, and particularly where a plurality of measuring hoppers of different dimensions should be operated together.

There is shown in the drawings a large, double, conical measuring hopper 10 and

a smaller measuring hopper 11. In Fig. 1 they are shown centrally broken away in several places, so that the height of each hopper is relatively greater than shown. 5 These hoppers consist really of two parts, the large and major portions 10 and 11, and the upper portions 110 and 111, the lower ends of which project partially into the lower or main portions and are surrounded 10 by the same. This latter feature of construction is not shown because it is common and well known in the art and is not a novel part of this invention. The upper or inlet end of each hopper flares upwardly 15 so as to be hopper-like for receiving the material to be measured from the outlet pan 12 located above it and which is the outlet for a large storage bin above the pan 12, not here shown. This storage bin 20 may be of several tons or a hundred tons capacity. The particular construction of this pan 12 is illustrated in Fig. 4. It has a wide rectangular rim 112 with inclined downwardly and inwardly tapering sides to 25 the outlet. In the constructions heretofore employed, the side walls of this pan have been circular, but one of the important improvements of this invention is providing said pan with an opening 14 in one side 30 thereof to receive the sand or material forced forward and upward as the valve is being closed, as shown in Fig. 5. The top 214 is a horizontal covering or plate here shown integral with the pan for keeping 35 the material above from entering and filling the opening 14 as the material flows through the pan or outlet.

On the arbor 15 mounted in one side of said pan, the shank 16 of a valve 17 is 40 pivoted or fulcrumed. This valve plate 17 is largely circular, but the advancing edge 117 is curved concavely from the shank towards the point 217 so that when the valve is being closed, as seen in Fig. 5, 45 it will move and push the material along the edge of the valve and out of the way so that it will not jam between the valve and the side walls 12 of the pan. When the valve is being closed, it must be forced 50 through the mass of crushed stone or the like and as the stone is incompressible, some space provision for the displaced material is necessary. This space is provided by chamber 14. As the valve is being 55 closed with material above and below, it must force some of the material forward and upward and since there may be several tons of material above, it is not possible to force it upward by the closing 60 movement of the valve unless there is provided the opening 14, which is not filled with material as it comes downward from the bin above.

The circular wall 12 is modified at the opening 14 to a V-shape in order to reduce

and check the forward movement of material by the valve when closing. The V-shaped section of wall 12 is extended beyond the closed position of the valve, thus serving to check but not positively stop the forward movement of material. 70

To enable the two valves of a pair to be simultaneously operated, there are arms 18 extending from the shanks 16 thereof which are connected by a connecting bar structure 75 19, as shown in Figs. 1 and 2. A hand lever 20 is connected with one of the valves for opening and closing it and when one is opened and closed, the other is given the same movement. 80

In the rapid operation of mechanism of this kind, as is necessary in practical use, the foregoing feature becomes of great value because stoppages of the mechanism by clogging or otherwise is very expensive as well 85 as annoying. It must always operate and the improvements above specified enable it to do so.

The valves 25 at the lower ends of the hoppers are pivoted at 26 in a frame 27 secured to the hopper, as shown in Figs. 1 and 2, so that they can swing downward in their opening movement, as seen in Fig. 2. Each valve has a fin or plate 28 on the back of it and centrally located with a stop 29 forming a part thereof adapted to engage the wall of the measuring hopper and limit the opening movement of the valve, as seen in Fig. 2. One valve is controlled by a hand lever 30 pivoted at 31 on an arm extending laterally from the frame 27 and forming a part of said frame. Said lever is pivoted between its ends and its inner end is connected with the plate 28 by a connecting bar 32. This is a toggle arrangement and is arranged so that when the valve is closed, the middle pivot will pass slightly beyond center, but will be prevented from further movement by a bent stop arm 33 which is rigidly connected with the lever 30 and 100 adapted to engage the outwardly extending arm from the frame 27, as seen in Fig. 1. 105

The other valve 25 for the right-hand measuring hopper is similarly constructed, but is controlled by a bell crank lever 34 115 which is operated through a long connecting rod 35 by a hand lever 36 fulcrumed at 31, beside the lever 30. This enables one person to operate both valves from one position simultaneously. The bell crank lever 34 has a stop 37 thereon adapted to engage the outward arm from the frame 27 in order to hold the toggle joint in place and hold the valve closed, accomplishing the same purpose as the stop 33. In order for this combined mechanism to operate well, the lower ends of the hoppers must be held in fixed position. Therefore, their lower ends (are connected by a rod 38. With this arrangement the slightest movement of the lever 30

or lever 36 will move the toggle joint past center on its return movement and then the way the material is resting on the valves will cause them to open.

5 The invention claimed is:

1. The combination of a bin outlet structure, a swinging horizontal valve for controlling said outlet, the advancing edge of said valve being curved concavely so as to 10 crowd away the material in the closing movement of the valve without jamming material between the valve and the bin outlet structure with which it is mounted.

2. The combination of a bin outlet structure, a swinging horizontal valve for controlling said outlet, the advancing edge being pointed at the end and slightly curved concavely therefrom to the shank so as to 15 shear through the material as it is being closed.

20 3. The combination of a bin outlet structure having an outlet passageway, a horizontally moveable valve pivoted to the structure at one side of the outlet, and an open-

ing at the side of the outlet towards which 25 the advancing edge of the valve moves while closing so that the valve will crowd the material into said opening, there being a plate above said opening to keep it from normally filling.

30 4. The combination of a bin outlet structure having an outlet passageway, a horizontally moveable valve pivoted to the structure at one side of the outlet, and an opening at the closing side of the outlet towards 35 which the advancing edge of the valve moves while closing so that the valve will crowd the displaced material into said opening, there being a plate above said opening to keep it from normally filling and there being no bottom to said opening but there being side walls to said opening inclined upwardly from the bottom of the outlet structure to said top plate.

40 In witness whereof, I have hereunto affixed my signature.

CHARLES S. JOHNSON.
